US00D948424S

(12) **United States Design Patent** (10) Patent No.: **US D948,424 S**
(45) Date of Patent: **** Apr. 12, 2022**

(54) **PORTABLE CHARGING STATION FOR ELECTRIC VEHICLES**

(71) Applicant: **Juice Technology AG**, Cham (CH)

(72) Inventor: **Christoph Erni**, Winkel (CH)

(**) Term: **15 Years**

(21) Appl. No.: **35/510,430**

(22) Filed: **Sep. 4, 2020**

(80) **Hague Agreement Data**

Int. Filing Date: **Sep. 4, 2020**

Int. Reg. No.: **DM/210425**

Int. Reg. Date: **Sep. 4, 2020**

Int. Reg. Pub. Date: **Oct. 2, 2020**

(51) **LOC (13) Cl.** **13-02**

(52) **U.S. Cl.**

USPC **D13/107**

(58) **Field of Classification Search**

USPC D13/107, 108, 120, 174, 102, 146;
D24/111

CPC B60L 53/18; H01R 13/6315

Primary Examiner — Rhea Shields

(57) **CLAIM**

The ornamental design for a portable charging station for electric vehicles, as shown and described.

DESCRIPTION

1.1 is a perspective view;

1.2 is a side view;

1.3 is a top view;

1.4 is a perspective view; and

1.5 is an end view.
